UNITED STATES PATENT OFFICE

2,326,465

CONTROL APPARATUS

Earl A. Keefer, Newington, Pa., assignor to The Brown Instrument Company, Philadelphia, Pa., a corporation of Pennsylvania

Application August 2, 1940, Serial No. 349,625

6 Claims (Cl. 171-149)

The present invention relates to improvements in voltage regulating apparatus.

An object of the invention is to provide improved apparatus for deriving a source of potential of high constancy from a commercial source of electric current notwithstanding the usual and substantial fluctuations in voltage of the commercial voltage source.

Another object of the invention is to provide apparatus for deriving a source of potential of high constancy from a commercial source of electric current notwithstanding the usual and substantial fluctuations in voltage and frequency of the commercial current source.

A further and more specific object of the invention is to provide improved voltage regulating apparatus of the constant potential transformer type by means of which variations of input voltage and frequency of the transformer may take place over a wide range without affecting the output voltage of the transformer to any significant extent.

A still further object of the invention is to provide improved voltage regulating apparatus of the type which does not utilize any mechanically movable parts and which is adapted to compensate for the variations in voltage and frequency of the energizing current source whereby the output voltage of the apparatus is maintained substantially constant to a high degree of accuracy notwithstanding the voltage and frequency changes of the energizing current source.

Voltage regulating devices of the constant potential transformer type which do not require the use of mechanically movable parts are well known. One such voltage regulator now in extensive commercial use, for example, is disclosed in Patent 2,143,745 issued January 10, 1939, to Joseph C. Sola. While the voltage regulator disclosed in that patent is adapted to maintain a voltage constant to a high degree of precision on a load circuit notwithstanding substantial fluctuations in voltage of the energizing current source, I have discovered that the accuracy of the voltage maintained can be improved to a substantial extent by providing an adjustable resistance properly connected to the transformer.

Accordingly, it is an object of the present invention to improve the operation of constant potential transformers by simple and efficient means.

A disadvantage of the voltage regulating apparatus known prior to my invention is that variations in the frequency of the energizing cur-

rent source produces a substantial error in the output voltage applied to the load circuit on which it is desired to maintain a constant voltage. Such error is produced because of the reactive character of the constant potential transformer. The reactance of the windings on the transformer is dependent upon the frequency of the energizing current source, and accordingly, if the frequency of the energizing current source changes, an accompanying change in reactance of the transformer windings is produced which is effective to cause error in the output voltage maintained by the transformer. In accordance with my present invention, such error is corrected or compensated for by interposing a reactive circuit between the output terminals of the constant potential transformer and the terminals of the load device on which it is desired to impress a current of constant voltage and frequency. In the preferred form of my invention, the reactive circuit referred to is comprised of resistance, inductance and capacitance which are connected in series across the output terminals of the constant potential transformer. The terminals of the load device on which it is desired to maintain a constant voltage are connected to the terminals of the capacitance. I have discovered that when the resistance, inductance and capacitance referred to are properly related to each other and to the characteristics of the constant potential transformer, the voltage maintained on the load device will be substantially constant notwithstanding wide variations in frequency and voltage of the energizing current source with the characteristics of the voltage regulating transformer, such that the output voltage thereof tends to increase with increase of frequency of the energizing voltage source and tends to decrease with decrease in frequency of the energizing voltage source. Under this condition, and with the capacitance and inductances properly chosen, the rise or drop of output voltage of the voltage regulating transformer upon change in frequency of the energizing current source is exactly compensated for or balanced out. While the precise operation of the constant potential transformer in conjunction with the reactive circuit referred to to produce this desired operation is not now known to me, it is believed that the compensation for frequency variations with the energizing voltage source is obtained partly because of the variable loading effect on the transformer produced by the reactive circuit and

partly because of the change in the division of the voltage across the resistance, inductance and capacitance of the reactive circuit upon change in frequency of the energizing current source. That is to say, at one frequency the reactive circuit presents a given impedance to the flow of current therethrough and the voltage is divided in one manner across the resistance, inductance and capacitance, whereas at another frequency the impedance presented by said reactive circuit is a different value and the voltage is divided in a different manner across the resistance, inductance and capacitance. When the resistance, inductance and capacitance comprising the reactive circuit are properly chosen with respect to each other and with respect to characteristics of the components of the constant potential transformer, it has been found that the tendency of the voltage across the capacitance to increase with increase of frequency or to decrease with decrease of frequency may be substantially eliminated.

The various features of novelty which characterize my invention are pointed out with particularity in the claims annexed to and forming a part of this specification. For a better understanding of the invention, however, its advantages and specific objects attained with its use, reference should be had to the accompanying drawing and descriptive matter in which I have illustrated a preferred embodiment of the invention.

Of the drawing:

Fig. 1 is a diagrammatic illustration of the wiring arrangement utilizing the construction shown in Fig. 2 and also illustrates the connection of the series connected inductance and capacitance comprising the reactive circuit for compensating for frequency variations of the energizing current source in accordance with my invention; and

Fig. 2 is a sectional view of one form of construction of a constant potential transformer type regulator with which my invention may be utilized.

In Fig. 1 of the drawing, I have illustrated more or less diagrammatically the use of the improved voltage regulator of my invention in maintaining a constant direct current potential across a potentiometer slidewire 1. A variable portion of the voltage across the slidewire 1 is opposed to the voltage developed by a thermocouple 2 which is inserted in a furnace 3 or other compartment, the temperature of which it is desired to ascertain. Differences in the voltage developed by the thermocouple 2 and the portion of the slide-wire voltage opposed thereto are detected by a sensitive voltmeter or galvanometer 4 which may be of the suspension or other suitable type. The portion of the voltage across the slidewire 1 opposed to the thermocouple voltage is adjustable by sliding a contact 5 along the slidewire. It will be apparent such adjustment of the contact 5 along the slidewire 1 may be effected automatically in any well known manner in response to the deflection of the movable element or pointer of the galvanometer 4, but for convenience and in order not to confuse the drawing, I have illustrated the contact 5 as manually adjustable along the slidewire 1 by manipulation of a knob 6.

In Fig. 2 I have illustrated a sectional view of a well known shell type of voltage compensating transformer which is sold commercially by the

Sola Electric Company of Chicago, Illinois. This transformer is disclosed in the Sola patent referred to hereinbefore.

As illustrated the voltage compensating transformer comprises two closed magnetic circuits 7 and 8, a central core bar 9 which may be made up of I-shaped laminations, the sides of which are in abutting contact with the end legs 10 of E-shaped laminations 11 and the end legs 12 of E-shaped laminations 13. The I-shaped and E-shaped laminations are clamped in operative relation by any suitable means.

A primary winding 15 is mounted on the left end of the core bar 9, as seen in the drawing. For convenience this end of the core bar has been designated the end portion 14. The terminals of the primary winding 15 are connected to the supply conductors L¹ and L², the voltage and frequency of which are variable. Another winding 16 is mounted on the right end portion of the core bar 9, which portion has been designated by the reference numeral 17. The winding 16 is spaced from the winding 15 but is magnetically coupled loosely therewith. As shown in Fig. 1, a condenser 18 is connected across the terminals of the winding 16. Another winding 19 is positioned over the winding 16 and is magnetically coupled therewith. One terminal 20 of the winding 19 comprises one terminal of the output circuit of the transformer. Another winding 21 is mounted on the end portion 14 of the core bar 9. The winding 21 is positioned over and is magnetically coupled tightly with the winding 15. A conductor 22 connects the right end terminal of the winding 21 to the other terminal of the winding 19. The windings 19 and 21, therefore, are connected in series with the output circuit of the transformer, the conductor 20 as mentioned hereinbefore comprising one output conductor of the transformer and a conductor 23 comprising another output conductor of the transformer. As illustrated, a portion of the turns of the winding 21 are shunted by a resistance 24 along which a contact 25 is adapted to be adjusted by manipulation of a knob 26. The conductor 23 is connected to the contact 25. With this arrangement the effective portion of the winding 21 in series with the winding 19 may be readily adjusted as desired. This is an important feature of my present invention since by facilitating this adjustment it is possible to effect much closer compensation for voltage variations of the alternating supply conductors L¹ and L². While the resistance 24 has been shown connected in shunt with a portion only of the winding 21, it will be understood that said resistance may be connected in shunt to the whole of the winding 21 if desired.

The closed magnetic circuits described are each provided with a high leakage reactance path between the windings 15 and 21 on the end portion 14 on the one hand and the windings 16 and 19 on the end portion 17 of said core bar on the other hand. As illustrated in the drawings, such high leakage reactance path comprises the central legs 27 and 28 of the respective E-shaped laminations 11 and 13. The legs 27 and 28 terminate short of the adjacent sides of the core bar 9 and thereby provide air gaps 29 and 30 between the legs 27 and 28 and the core bar 9.

The principle of operation of the voltage regulating transformer shown in Fig. 2 and shown by the dotted part of Fig. 1 is clearly set forth in the aforementioned Sola Patent 2,143,745 and, therefore, will not be elaborated on herein. For

the purposes of the present invention, it is believed sufficient to note that the flux set up by applying a voltage across the primary winding 15 will link with the winding 16 and cause a definite reactance to be set up by the latter. As the voltage on the primary winding 15 is increased from zero to a higher level, the flux passing through the winding 16 tends to increase in nearly direct proportion to the primary flux because of the reluctance caused by the air gaps 29 and 30, a very small amount of flux leaking through the legs 27 and 28. As the voltage induced in the winding 16 increases, a critical point is reached where resonance takes place. Under this resonant condition a definite amount of current flows through the winding 16 and the condenser 18, which current will be limited by the constants of the winding 16 and the condenser 18 with the result that a substantially constant potential will be set up across the winding 16, as explained hereinafter, and a corresponding amount of magnetic flux will be set up in the end portion 17 of the core bar 9.

By virtue of the inherent characteristic of a resonant circuit that its power vector may be many times greater than that of the generator which supplies the energy to the resonant circuit, the change in flux density in section 14 of the core bar 9 due to variations in the voltage of the supply conductors L^1 and L^2 will have no appreciable effect on the resonant circuit as long as the magnetic density of the section 14 of the core bar remains under the maximum density of section 17 of the core bar. This effect is obtained since the reluctance of the leakage path through the legs 27 and 28 is then less than the reluctance of the section 17 of the core bar whereby flux will leak through said leakage path between the primary and resonant core portions.

Because of this leakage reluctance path the coefficient of coupling between the primary winding 15 and the resonant circuit including winding 16 and condenser 18 is reduced to a certain optimum value, thereby maintaining a balanced condition, so that the resonant circuit will continue to oscillate with the maximum current therein at a frequency equal to the frequency impressed on the primary winding. With this state of resonance obtained, the winding 16 will set up a magnetic field in the core section 17 which will remain practically constant so long as the density in the magnetic field of the core portion 14 remains at a lower density than that of the core portion 17. This substantially constant flow of flux in the core portion 17 operates to produce a substantially constant voltage across the terminals of winding 16 and condenser 18, which voltage will remain practically constant irrespective of variations in the voltage applied to the terminals of the primary winding 15.

The resonant circuit including winding 16 and condenser 18 therefore provides a constant primary source of voltage for the winding 19. The output voltage of the winding 19 will therefore have a practically constant voltage level independent of the voltage variations in the primary winding 15 so long as the circuit including winding 16 and the condenser 18 remain in resonance.

The winding 21 is coupled to the portion 14 of the core bar 9 so that upon variation in the voltage applied to the terminals of the winding 15, corresponding variations in the voltage across the terminals of the winding 21 are produced. That is to say, the voltage induced in the wind-

ing 21 will always be proportional to the turns ratio of primary winding 15 and winding 21.

An extremely constant level of voltage may be maintained between the output conductors 20 and 23 of the voltage regulating transformer by suitably apportioning the number of effective turns on the winding 21 in relation to the number of turns on the winding 19. Or, if desired, any percentage of regulation of output voltage in relation to variations of the voltage of the alternating supply conductors L^1 and L^2 may be obtained at the conductors 20 and 23 by properly arranging or proportioning winding 21 in relation to the winding 19. For example, if desired it is possible to produce a decrease in the voltage between the conductors 20 and 23 upon an increase in the voltage of the supply conductors L^1 and L^2 . The provision of the resistance 24 and slidable contact 25 greatly facilitates such apportioning of the effective turns of winding 21 connected in circuit with the winding 19. I regard the provision of the resistance 24 and adjustable contact 25 as an important feature of my present invention, since by its use the need for careful winding of the precise number of turns on the winding 21 is eliminated thereby effecting a substantial reduction in the cost of constructing the transformer.

The operation of the voltage regulating transformer described has so far been upon the assumption that the output conductors 20 and 23 are open circuited, that is to say, are not connected to a load circuit. If a load is connected to the conductors 20 and 23, however, a magnetic flux will be developed in the resonant circuit including the conductor 16 and condenser 18, which magnetic flux will correspond to the load connected to the conductors 20 and 23. This operates to unbalance the magnetic flux in section 17 of the core. This change in magnetic flux in the portion 17 of the core, in turn, affects the stable relation of the flux in the core sections 14 and 17 and also the leakage reactance through the shunt paths 27 and 28 and thereby causes more useful flux from the core section 14 to pass through the core section 17, which change in flux through the core 17 compensates for the energy used by the load circuit and at the same time maintains the resonant circuit in the desired oscillating condition.

The operation of the voltage regulating apparatus described so far has been upon the assumption that the frequency of the alternating voltage of the supply conductors is constant. Upon variation in said frequency, however, the inductive reactance of the windings 15, 16, 19 and 21 of the voltage regulating transformer is varied correspondingly and as a result the magnetic flux in section 17 of the core bar 9 is varied. This change in flux through section 17 affects the stable relation of the flux in the core sections 17 and 14 and, unless compensated for, would result in the establishment of a different voltage between the output conductors 20 and 23 of the voltage regulating transformer. Thus, changes in frequency of the alternating voltage of supply conductors L^1 and L^2 tend to produce error in the output voltage of the voltage compensated transformer.

In accordance with my present invention such variations in output voltage of the voltage regulating transformer upon variation in the frequency of the alternating supply conductors L^1 and L^2 are corrected or compensated for by interposing a reactive circuit between the output con-

ductors of the regulating transformer and the load device. As illustrated this reactive circuit includes an adjustable resistance 31, an inductance 32 and a capacitance 33 which are connected in series between the output conductors 20 and 23 of the transformer. The resistance 31 may be adjusted by manipulation of a knob 34. The terminals of the capacitance 33 are connected to the terminals of the load device on which it is desired to maintain a constant potential.

The series connected resistance 31, inductance 32 and condenser 33 may be regarded as a frequency responsive circuit which operates to vary the load on the output circuit of the voltage regulating transformer upon variation in frequency of the alternating supply conductors L¹ and L². By properly proportioning resistance 31, inductance 32 and capacitance 33, the load on the output circuit of the voltage regulating transformer is automatically varied to at least partly compensate for the effect produced in the transformer by the change in frequency of the impressed alternating voltage. That is to say, the density change produced in the core section 17 as a result of the change in frequency of the alternating voltage supply conductors L¹ and L² is at least partly corrected or compensated for by the change in load on the output circuit of the transformer produced by the series connected resistance 31, inductance 32 and capacitance 33. The remainder of the compensation needed to overcome the effect of the change in frequency of the alternating supply conductors L¹ and L² is believed to be obtained as a result of the change in division of the voltage across the elements 31, 32 and 33 of the reactive circuit. That is to say, at one frequency of the voltage of the supply conductors, the output voltage of the transformer will be divided in one manner across the elements 31, 32 and 33 of the reactive circuit, and as said frequency changes, the division of the transformer output voltage across said elements 31, 32 and 33 is correspondingly varied. These two compensating effects combine to produce the precise amount of compensation required to neutralize the effect of the line voltage frequency change on the voltage across the terminals of capacitor 33. By way of illustration, when the voltage compensating transformer embraced by the dotted lines in Fig. 1 is a "Sola Compensated Transformer" having the following rating:

Primary volts—95-125 at 60 cycles/sec.

Secondary volts—20±1% with an output of 10 volt-amperes.

The voltage across the terminals of the condenser 33 may be maintained constant to within one-half of one percent variation upon an increase in line voltage from 95 volts to 125 volts and with a frequency shift of from 54 cycles per second to 68 cycles per second when the resistance of the resistance 31 is 50 ohms, the inductance of the inductance 32 is 0.75 Henry at 0.5 M. A., the D. C. resistance of inductance 32 being 30 ohms, and the capacitance of the condenser 33 is 30.5 microfarads. Under these conditions, I have determined that the voltage between the conductors 20 and 23 is 19 volts and the voltage across the terminals of the condenser 33 is 9.8 volts.

In the form of my invention disclosed in Fig. 1, the voltage across the terminals of the condenser 33 is applied to the terminals of a full wave rectifier 35 which may be of the copper oxide or other suitable type and the output ter-

minals with the latter are connected through an adjustable resistance 36 to the terminals of the slidewire resistance 1.

While I have illustrated the use of my invention for maintaining a constant voltage across a potentiometer slidewire used for measuring the voltage developed by a thermocouple, it will be understood that my invention is not limited to such use but that it has numerous other advantageous uses.

While in accordance with the provisions of the statutes, I have illustrated and described the best form of my invention now known to me, it will be apparent to those skilled in the art that changes may be made in the form of the apparatus disclosed without departing from the spirit of my invention as set forth in the appended claims, and that in some cases certain features of my invention may sometimes be used to advantage without a corresponding use of other features.

Having now described my invention, what I claim as new and desire to secure by Letters Patent is:

1. Control apparatus comprising the combination of a magnetic core, a winding on said core adapted to be connected to a source of fluctuating voltage, a second winding on said core in spaced relation to said first mentioned winding, a reactive circuit including resistive, inductive and capacitive components, a third winding on said core in inductive relation to the first mentioned winding and connected in series with said second mentioned winding and said reactive circuit, an output circuit connected across the capacitive component of said reactive circuit, said core providing a high leakage reactance path for a portion of the flux to thread through said first and third windings to the exclusion of said second winding, a resonant circuit including a condenser and a fourth winding, the resonant circuit operating at a frequency substantially equal to the frequency of said source, the fourth winding being in inductive relation to the second winding, and means to adjust the relative effective portions of said second and third windings which are connected in series.

2. The combination of claim 1 wherein the last mentioned means comprises a resistance connected in shunt to said third winding and a contact adjustable along the length of said resistance.

3. Control apparatus comprising the combination of a magnetic core, a winding on said core adapted to be connected to a source of fluctuating voltage, a second winding on said core, said core providing a high leakage reactance path for a portion of the flux to thread through one of the windings to the exclusion of the other winding, a reactive circuit including resistive, inductive and capacitive components connected across the terminals of said second winding, an output circuit connected across the capacitive component of said reactive circuit, and means for maintaining the potential across said output circuit substantially constant irrespective of fluctuations in the voltage of said source comprising a resonant circuit including a condenser and a third winding, the resonant circuit operating at a frequency substantially equal to the frequency of the voltage impressed on the first mentioned winding, the third winding being in inductive relation to said second winding.

4. Control apparatus comprising the combination of a magnetic core, a winding on said core

adapted to be connected to a source of fluctuating voltage, an output circuit, a second winding on said core adapted to be connected to said output circuit, a third winding on said core, said core providing a high leakage path for a portion of the flux to thread through one of the windings to the exclusion of the other winding, means for maintaining the potential across the output circuit substantially constant irrespective of fluctuations in said source of voltage comprising a resonant circuit including said third winding and a condenser, the resonant circuit operating at a frequency substantially equal to the frequency of the voltage impressed on the first winding, and means for maintaining the potential across the output circuit substantially constant irrespective of variations of frequency of said source of voltage including a condenser and an inductance connected across said second winding, the output circuit being connected across said last mentioned condenser.

5. Control apparatus including in combination a constant potential transformer having an input circuit and an output circuit, a source of fluctuating voltage connected to the input circuit of said transformer, said transformer being characterized by the fact that it operates to maintain the voltage across its output circuit substantially constant irrespective of fluctuations in the voltage of said source, a load circuit connected to the output circuit of said transformer, and means for maintaining the potential across said load circuit substantially constant irrespective of fluctuations in the frequency of said source comprising a reactive circuit interposed between 10 said load circuit and the output circuit of said transformer.
- 15 6. The combination of claim 5 wherein the reactive circuit includes resistive, capacitive and inductive components, and the load circuit is connected across the capacitive component.

EARL A. KEELER.
